(57) **CLAIM**

The ornamental design for an expandable measuring gauge, as shown and described.

DESCRIPTION

FIG. 1 is a front, top, right isometric perspective view of an expandable measuring gauge in accordance with a first embodiment of our design;

FIG. 2 is a top plan view of the expandable measuring gauge of FIG. 1;

FIG. 3 is a bottom plan view of the expandable measuring gauge of FIG. 1;

FIG. 4 is a front elevation view of the expandable measuring gauge of FIG. 1;

FIG. 5 is a rear elevation view of the expandable measuring gauge of FIG. 1;

FIG. 6 is a right side elevation view of the expandable measuring gauge of FIG. 1; and,

FIG. 7 is a left side elevation view of the expandable measuring gauge of FIG. 1.

The broken lines illustrate portions which form no part of the claimed design.
